METHOD OF AND APPARATUS FOR LABORATORY INVESTIGATION OF THE ROLLING OF SHIPS

Julius Gravrogkas, Cleveland, Ohio

Application July 16, 1952, Serial No. 299,181

15 Claims. (Cl. 35—19)

1

This invention relates generally to a method of and apparatus for determining or investigating the rolling of ships.

In the stabilizing of ships by means of gyroscopes, it is important to know exactly how the proposed means of stabilizing will affect the ship as soon as it is tossed about by the ocean waves.

It has heretofore been necessary, for the purpose of such determinations, to take the ship to sea. This method is, however, inconvenient and disadvantageous in many respects, including the following:

(a) It is extremely expensive.

(b) Since the ocean waves cannot be varied as desired, they must be considered or taken as of the time the investigation is being conducted.

(c) The results achieved by such an expensive method are valid only for those ships for which the proportions between the mechanical quantities defining the tossing or rolling are the same as those of the ship under investigation.

(d) It doesn't allow a general decision to be made because to make a general and final decision about gyroscopic stability of ships it is necessary to have a possibility to change the mentioned proportions within sufficiently wide limits as well as the rolling moment which affects the ship.

The present invention has as its primary object a method of and apparatus for determining or defining of the resistance of any stabilized ship when affected by waves of various frequencies, and which method and apparatus overcomes all the aforesaid disadvantages of prior methods.

My invention comprises an apparatus and method for laboratory investigation which enable the following things to be accomplished:

1. The representation by means of movable parts, of the rolling motion of any ship which is stabilized by means of gyroscopes.

2. The provoking of the rolling moment which should correspond to any strength of the waves.

3. The selection, in a most effective way, of stabilizing equipment or parts necessary to stabilize a ship subjected to tossing about by waves.

4. The use of the apparatus as a teaching medium for leashed oscillations.

5. Learning how to remove the trouble, if any arises, because of gyroscopic stabilization of ships.

Other objects and advantages of the invention will become apparent during the course of the following description, taken in connection with the accompanying drawings, in which like numerals designate like parts throughout, and in which

Fig. 1 is a side elevational view of one side of the apparatus embodying the invention;

Fig. 2 is a side elevational view of the opposite side of the apparatus;

Fig. 3 is a view, partly in end elevation, and partly in section, showing the construction of various parts of the apparatus;

2

Fig. 4 is a transverse cross-sectional view, taken on the line A—B of Fig. 3, and

Fig. 5 is an elevational detail of certain related parts of the apparatus whereby motion of rotation is converted into reciprocating motion.

Referring more particularly to the drawings, the apparatus will be seen to comprise a pendulum 10 to which a shaft 11, journaled at its ends in standards 12 and 13 of a frame 14, is rigidly secured. The standards, which are channel-shaped in section, are spaced apart and their lower ends extend between and are secured to spaced channel-shaped base members 15 and 16 as by means of bolts or the like and by means of pairs of gussets 17 and 18. A bolt 19 carrying a sleeve 20 secures the lower ends of the standards together.

The pendulum 10 embodies spaced channel-shaped members 21 and 22, the upper and lower ends of which are connected by similar channel-shaped transverse members welded to the members 21 and 22. The plates 23 and 24, which are secured to the aligned nanges 25 and 26 and to the aligned flanges 27 and 28 of the members 21 and 22, carry the shaft 11.

Unthreaded round bars 29 and 30 are located on one side of and parallel to the members 21 and 22 and similar bars 31 and 32 are located on the other side of and parallel to these members. The bars 29 and 31 are secured in spaced relationship to the member 21 being secured to the top thereof by means of Z-shaped clips 33 and 34 bolted, respectively, to the flanges 27 and 21, and angle members 35 and 36 bolted to the clips.

The upper ends of the bars 29 and 31 are threaded and extend through openings in the angle members to which they are secured by nuts 37 and 38 threaded upon the ends of the bars. The bars 29 and 31 are similarly secured at their lower ends in spaced relationship to the member 21 by means of Z-shaped clips 39 and 40 and angle members 41 and 42 into which the bars extend. The bars 30 and 32 are similarly secured to the channel-shaped member 22 of the pendulum.

The bars 29, 30, 31 and 32 carry internally threaded weights 43 and 44, 45 and 46, 47 and 48 and 49 and 50, respectively. This permits the weights to be adjusted along the bars and thereby vary the moment of inertia of the pendulum so that its height may be kept within reasonable limits.

A motor 51 is secured in any desired manner upon the pendulum 10. The shaft 52 of the motor lies parallel to the pendulum and is extended and connected to a worm 53 which is in mesh with a worm gear 54 fixedly secured upon a shaft 55. A series of gears 56 of progressively decreasing diameter are mounted upon shaft 55. The gears of this series are adapted to mesh selectively with the corresponding gears of a series

of gears 51 of progressively increasing diameter so as to vary the angular velocity of shaft 58 upon which the gears of the latter series are mounted.

A disc 59 is fixedly secured upon one end of shaft 58. The disc is formed with a diametrical slot 60 through which a bolt 61 extends for securement to the disc at various distances from its center. The bolt 61 extends through a slot 62 formed in a slide 63 which is guided in its vertical linear movement by a frame 64. The disc and bolt accordingly impart a vertical reciprocating motion to the slide 63 the extent of which is determined by the distance of the bolt from the center of the disc.

A sprocket chain 65 is secured to the slide 63 and passes around sprocket wheels 66 and 67. The lower sprocket wheel is rotatably mounted upon a stub shaft 68 secured to member 22 of the pendulum 10. The upper sprocket wheel 67 is fixedly mounted upon a shaft 69 which is journaled in the members 21 and 22 of the pendulum. The shaft 69 embodies a ring in which the electric motor 70 of a gyroscope 71 is firmly held. Separate discs 72 and 73 are mounted upon the shaft of the motor and constitute selectively variable flywheels for the gyroscope.

The pendulum 10 also carries a gyroscope 74 the electric motor 75 of which is firmly held in a ring embodied in a shaft 76 journaled in the members 21 and 22 of the pendulum 10 above gyroscope 71. Separate discs (not shown) similar to the discs 72 and 73 can be mounted upon the ends of the shaft of motor 75 and serve the same purpose as discs 72 and 73.

The shaft 76 carries a disc 77 which revolves between the adjustable poles of an electromagnet 78 which therefore exerts a braking moment upon the gyroscope 74 whose function is to stabilize the swing of the pendulum. In place of adjustable poles change in the current of the electromagnet 78 may be resorted to in order to vary the value of the braking moment.

The moment of inertia of the gyroscope 74 about the axis of the shaft 76 is made variable by means of pairs of weights 79 and 80 and 81 and 82. The weights 79 and 80 are adjustably mounted upon a rod 83 suitably secured to the shaft 76. The weights 81 and 82 are adjustably mounted upon a rod 84 secured to the shaft 76. Various weights 85 can be secured to the shaft 76 to change the frequency of oscillation of gyroscope 74 about the shaft 76.

A gear 86 is fixed upon shaft 11 so as to oscillate with the shaft. Gear 86 is meshed with a rack bar 87 slidably received within a guide 88 carried by the standard 12 so that oscillation of the gear 86 produces a vertical reciprocating motion of the rack bar. A similar motion is produced in a stylus 89 secured to the rack bar. The stylus bears upon a paper wrapped around a drum assembly 90 which rotates at a constant speed so as to trace a curve upon the paper. An indicator diagram is thus formed the ordinates of which are a measure of the angular deflections of the oscillation of the pendulum.

As heretofore noted the apparatus described

hereinabove can be utilized to conduct investigations in the laboratory for the purpose of determining in an economical manner how to gyroscopically stabilize the rolling motion of ships produced by ocean waves of different frequencies. The procedure heretofore employed of investigating the subject ship by actually submitting it to the action of ocean waves was not only prohibitively expensive but the results obtained were so uncertain as to render impractical the idea of gyroscopically stabilizing the rolling motion of ships. The apparatus described above renders such investigations economical and translates the idea of gyroscopic stabilization of the rolling motion of ships into an exact and practical science. This apparatus, moreover, can be utilized to teach gyroscopic action since quantitative results can be achieved.

The pendulum 10 of such apparatus is projected upon the differential equations

$$I_y \frac{d^2\varphi}{dt^2} - I_z \omega \frac{d\psi}{dt} + M_s \varphi - M_s \varphi_0 \sin \gamma t = 0$$

$$I_z \frac{d^2\psi}{dt^2} + I_z \omega \frac{d\varphi}{dt} + m_s \psi + m_z \frac{d\varphi}{dt} = 0$$

The first differential equation represents the equation of the rolling motion of a ship and the second the equation of the oscillatory motion of a gyroscope together with its frame within the ship. In these equations

I_y =the moment of inertia of the ship and the gyroscope within it about the longitudinal axis of the ship.

I_z =the moment of inertia of the gyroscope together with its frame about the transverse axis about which the frame rotates.

I_z =the moment of inertia of the gyroscope about its axis.

M_s =the result obtained by multiplying the weight of the ship by its metacentric height. This result is referred to as the moment of oscillation of the ship.

m_s =the product of the weight of the gyroscope and its frame by the distance from their center of gravity to the transverse axis about which the frame rotates. This is referred to as the moment of oscillation of the gyroscope and its frame.

m_z =the brake moment acting upon the frame of the gyroscope. Its magnitude corresponds to the unit of the angular velocity of the frame. This moment is referred to as the brake number.

ω =the axial angular velocity of the gyroscope.

γ =the frequency of oscillation of the ocean waves.

φ_0 =the maximum angle of inclination of the waves.

φ =the heeling angle of the ship.

ψ =the angle of inclination between the axis of the gyroscope and the high axis of the ship.

From the two equations noted above an equation is derived from which the maximum heeling angle of a ship may be calculated. This equation is

$$\left[\frac{m_s}{I_z} - \frac{\gamma^2}{M_s} \right]^2 + \frac{\gamma^2}{M_s} \cdot \frac{\left(\frac{M_s}{I_z} \right)^2}{I_y} \cdot \frac{M_s}{I_y} \cdot \frac{M_s}{I_y}$$

$$\varphi_{\max}^2 = \varphi_0^2 \left[\frac{I_z^2 \omega^2}{I_y I_z} \cdot \frac{\gamma^2}{M_s} - \left(1 - \frac{\gamma^2}{M_s} \right) \left[\frac{m_s}{I_z} - \frac{\gamma^2}{M_s} \right] \right]^2 + \frac{\left(\frac{M_s}{I_z} \right)^2}{M_s} \cdot \frac{\gamma^2}{I_y} \cdot \frac{M_s}{I_y} \left[1 - \frac{\gamma^2}{M_s} \right]^2$$

5

An analysis of the immediately foregoing equation shows that the maximum heeling angle of the ship depends upon the following quantities:

1. The ratios

$$\frac{m_s}{I_x} \text{ and } \frac{M_s}{I_y}$$

or upon the frequencies of the free oscillation of the gyroscope together with its frame and of the ship.

2. The ratio

$$\frac{m_s}{I_z}$$

that is, upon the braking strength compared to the moment of inertia of the gyroscope and its frame about the transverse axis about which the frame rotates.

3. The ratio

$$\frac{I_z^2 \omega^2}{I_x I_y}$$

known as the swing number, and

4. The frequency of the waves as well as upon the maximum angle of inclination of the waves and therefore upon the rolling moment, $M_s \varphi_0 \sin \gamma t$ which acts upon the ship on the ocean.

In order that the apparatus hereinbefore described may be utilized for the indicated purpose the pendulum 10 is first calibrated so that its oscillation will be identical with the known oscillation of a ship having the greatest frequency of free oscillation of interest. As such a ship I chose the *Sylvana* used by Schlick, the famous inventor of the stabilization of ships by means of gyroscopes, in carrying out his experiments in the expensive and laborious manner heretofore noted. The numerical values hereinafter appearing were obtained from the *Sylvana*.

First, however, it is desired to set forth certain clarifying observations. The expression $M_s \varphi$ is equal to and is applicable to pendulum 10 as well as the ship. When the equation $M_s \varphi = QH\varphi$ is applied to the pendulum of the apparatus Q equals the weight of the pendulum and H equals the distance from the center of gravity of the pendulum to the axis about which the pendulum swings. Correspondingly the expressions M_s and φ equal the moment of oscillation and the angle of deflection of the pendulum. When the equation $M_s \varphi = QH\varphi$ is applied to the ship Q equals the weight of the ship, H the metacentric height, φ the heeling angle and M_s the moment of oscillation of the ship. Obviously, the moment $M_s \varphi$ acts upon the pendulum in the same way as the analogous moment acts upon the ship.

There is another moment which also acts upon the ship from without. This is the rolling moment $M_s \varphi_0 \sin \gamma t$. M_s in this expression equals the oscillation moment of the ship. An analogous moment must be applied to the pendulum. If the expression $M_s \varphi_0 \sin \gamma t$ is applied to the pendulum M_s equals the oscillation moment of the pendulum. The rolling moment $M_s \varphi_0 \sin \gamma t$ which must act on the pendulum is realized in such a way.

Continuing these observations and referring to the described apparatus it will be shown below that the angular velocity γ of the shaft 58 corresponds to the frequency of the ocean waves. The disc 59, which is fastened upon shaft 58, accordingly rotates with an angular velocity γ as does the bolt 61. When the bolt is placed at a distance "r" from the center of the disc and rotates with an angular velocity γ , it describes from

6

its lowest position during time "t" an angle γt and therefore its vertical displacement equals $(r - r \cos \gamma t)$ (Fig. 5). Since this is also the vertical displacement of the slide 63 through 5 which bolt 61 extends the velocity of the slide is $r\gamma \sin \gamma t$.

The motion of the slide is transmitted to the sprocket wheels 66 and 67 by means of the chain 65 fastened to the slide. The peripheral velocity of the sprocket wheels is therefore $r\gamma \sin \gamma t$ and their angular velocity

$$\omega_1 = \frac{r\gamma \sin \gamma t}{R}$$

15 where R equals the radius of the wheels.

The sprocket wheel 67 is fastened upon and transmits its rotation to the shaft 69 which carries the motor 70 of the gyroscope 71. When the sprocket wheel 67 rotates clockwise thru a certain 20 angle and then counter-clockwise thru the same angle the gyroscope 71 swings with the angular velocity ω_1 about the axis of shaft 69. Therefore a moment $I\omega_1 \omega_1$ arises. Since

$$\omega_1 = \frac{r\gamma \sin \gamma t}{R}, I\omega_1 \omega_1 = \frac{I\omega_1 r\gamma \sin \gamma t}{R}$$

where I equals the moment of inertia of the gyroscope about its axis and ω_1 its angular velocity about its axis. The moment

$$\frac{I\omega_1 r\gamma \sin \gamma t}{R}$$

acts upon the pendulum and realizes the rolling moment $M_s \varphi_0 \sin \gamma t$ which corresponds to the 35 analogous rolling moment which acts upon the ship on the ocean so that

$$\frac{I\omega_1 r\gamma \sin \gamma t}{R} = M_s \varphi_0 \sin \gamma t$$

40 In the foregoing equation the angular velocity γ of the shaft 58 corresponds to the frequency of the ocean waves, the relation

$$\frac{r}{R}$$

45 corresponds to the greatest angle of inclination of the ocean waves and the product $I\omega_1 r$ to the moment of oscillation of the pendulum. Since the distance r of the bolt 61 from the center of the disc 59 as well as the axial moment of inertia I 50 of the gyroscope 71 can be varied the relation

$$\frac{r}{R}$$

can be made equal to the greatest angle φ_0 of 55 inclination of the ocean waves and the product $I\omega_1 r$ to the moment M_s of oscillation of the pendulum.

To obtain the stabilizing moment which must act on the pendulum and correspond to the analogous moment which acts on the ship the gyroscope 60 71 is mounted upon the pendulum. This gyroscope functions to stabilize the swing of the pendulum.

Turning again to the calibration of the apparatus so that the oscillation of the pendulum will agree with the rolling motion of the ship *Sylvana*, consideration is had of the ratios hereinabove referred to which determine this oscillation. First is the ratio

$$\frac{M_s}{I_y}$$

wherein I_y is the moment of inertia of the ship *Sylvana* about its longitudinal axis or the moment of inertia of the pendulum about its axis

11, and M_s is the moment of oscillation of the ship or the pendulum. The moment of inertia of the pendulum consists of two parts, namely, the moment of inertia of the weights 43 to 50, inclusive, or I_y and the moment of inertia of the pendulum and the members fastened to it, or I''_y . The moment of inertia, I''_y , can be varied within limits by varying the position of the weights; the moment of inertia I''_y is constant. The pendulum is so designed that when the weights are placed at the maximum distance from shaft 11 the ratio

$$\frac{M_s}{I_y}$$

of the pendulum is equal to the analogous ratio of the ship *Sylvana*, namely

$$0.73^2$$

Also $I_y = I''_y - I'_y = 204 + 20 = 224$ kgm. sec.² and $M_s = 119$ kgm. Therefore,

$$\frac{M_s}{I_y} = \frac{119}{224} = 0.73^2$$

The swing number of the pendulum

$$\frac{I_z^2 \omega^2}{I_x I_y}$$

is next considered. In this expression, I_x which is the moment of inertia of the gyroscope 74 about transverse axis 76 consists of two parts, variable I'_x and constant I''_x . The value of I'_x depends upon the location of the movable weights 79 to 82, inclusive, while the value of I''_x depends upon the gyroscope 74 and the members connected with it and with the shaft 76. When the weights 79 to 82, inclusive, are placed as shown the magnitude of $I'_x = 0.18$ kgm. sec.². The value of $I''_x = 0.009$ kgm. sec.². Therefore, I_x which equals $I'_x + I''_x$ is equal to 0.189 kgm. sec.². The swing number of the *Sylvana* was twenty times as large as the square of its frequency of oscillation. To obtain correspondence between the pendulum and the ship *Sylvana* the angular velocity ω of the gyroscope 74 about its axis must be calculated from the equation

$$\frac{I_z^2 \omega^2}{I_x I_y} = 20 \frac{M_s}{I_y}$$

Since the values of I_x , I_y , ω and the frequency of oscillation,

$$\sqrt{\frac{M_s}{I_y}}$$

are known a value of ω can be obtained. The swing number of the pendulum then becomes equal to the swing number of the ship *Sylvana*.

The next ratio to be considered is

$$\frac{m_s}{I_x}$$

Since the frequency of oscillation of the gyroscope including its frame on the *Sylvana* is equal to the frequency of oscillation of the ship it-

$$\frac{m_s}{I_x} = \frac{M_s}{I_y} = 0.73^2$$

This equation takes into account the gyroscope, its ring, transverse shaft, the members fastened to it and the shown position of the weights 79 to 82, inclusive. The value of m_s as well as the above shown value of I_x satisfy the noted equation.

As to the ratio

$$\frac{m_s}{I_x}$$

various values must be assigned to m_s to ascertain its applicable value. These values can be obtained by means of the movable poles of the electromagnet 78. By moving the poles and enclosing more or less of the disc 77 different values of the brake number are obtainable. These values may, of course, be obtained by varying the current in the electromagnet 78 rather than by moving the poles.

It has been demonstrated herein that the maximum heeling angle of the ship is determined by the ratios

$$\frac{M_s}{I_y}, \frac{m_s}{I_x}, \frac{I_z^2 \omega^2}{I_x I_y}$$

as well as by the rolling moment $M_s \varphi_0 \sin \gamma t$. Therefore, if the noted ratios referred to the pendulum are equal to the same ratios referred to the *Sylvana*, the oscillation of the pendulum reproduces the rolling of the *Sylvana* and permits investigation of the rolling of the *Sylvana* when it is influenced by various ocean waves. Thus, the pendulum can be used to reproduce the rolling motion of the *Sylvana* when the frequency of the ocean waves is γ' and the greatest angle of inclination of such waves is φ_0' . The bolt 61 is moved along the slot 60 in the disc 59 a distance r' so that the ratio

$$\frac{r'}{R} = \varphi_0'$$

Then using the series of gears 56 and 57 I can cause the shaft 58 to rotate with angular velocity γ' . Finally, the necessary weights are added to the shaft of motor 70 in order to equate the product $I \omega_2 \gamma'$ to the moment of oscillation M_s of the pendulum. It follows that the swinging amplitude of pendulum will be equal to φ_0 max. which is the rolling amplitude of the *Sylvana* when it is acted upon by ocean waves having a frequency γ' and the greatest angle of inclination φ_0' .

The apparatus can be used to reproduce the rolling motion of ships having a frequency of oscillation which is less than that of the *Sylvana*. To demonstrate this it is first necessary to investigate the reproduction by the pendulum of the reduced rolling phenomenon of the known ship *Sylvana*. It may be assumed, accordingly, that the ocean wave oscillation is accelerated n times and that the waves are correspondingly reduced without changing their shape. While the frequency of oscillation of the actual ocean waves is γ' yielding a period of oscillation of

$$\frac{2\pi}{\gamma'}$$

the assumed frequency and period of oscillation become γ_1 and

$$\frac{2\pi}{\gamma_1}$$

respectively, where $\gamma_1 = n \gamma'$. On the other hand, I imagine that the corresponding mechanical magnitudes, upon which the rolling motion of the ship *Sylvana* depends, are so changed that the maximum heeling angle is retained. It can be obtained if the values of the ratios

$\frac{m_s}{I_x}, \frac{(m_s)^2}{I_x}, \frac{I_z^2 \omega^2}{I_x I_y}$ and $\frac{I_z^2 \omega^2}{I_y I_x M_s}$

can be retained.

A rolling phenomenon of the *Sylvana* is then considered so that the moments of oscillation M_s and m_s retain their values and only the moments of inertia I_x , I_y and I_z as well as the brake number m_z change in value. These moments of inertia and the brake number then become I'_x , I'_y and I'_z , and m'_z , respectively, so that the following equations are satisfied:

$$1. \frac{\gamma'^2}{M_s} = \frac{\gamma_1^2}{I'_y}$$

$$2. \frac{(m_z)^2}{I_x} = \frac{(m'_z)^2}{I'_x}$$

$$3. \frac{(m_z)}{I_x} = \frac{(m_s)}{I'_y}$$

$$4. \frac{I_x^2 \omega^2}{I_x I_y} \cdot \frac{1}{M_s} = \frac{(I'_x \omega)^2}{I'_x I'_y} \cdot \frac{1}{M_s}$$

Since $\gamma_1 = n\gamma'$, the above equations are valid if

$$I'_y = \frac{I_y}{n^2}; \quad I'_x = \frac{I_x}{n^2}; \quad m'_z = \frac{m_z}{n}; \quad \text{and} \quad I'_z = \frac{I_z}{n}$$

From the foregoing it is concluded that if the period of oscillation of the ocean waves is reduced n times, and if at the same time the moments of inertia I_x and I_y of the *Sylvana* are reduced n^2 times and the moment of inertia of the gyroscope stabilizer I_z and the brake number m_z are respectively reduced n times the maximum heeling angle of the *Sylvana* would be unchanged.

This conclusion has equal validity for every ship. It is also valid for the pendulum of the described apparatus because the Equations 1, 2, 3 and 4 expressed above are applicable as well to the pendulum. Of course we can only imagine the above mentioned change of oscillation of the sea waves as well as the corresponding changes in I_x , I_y , I_z and m_z of the ship *Sylvana*. But all considered changes can be realized on the pendulum and in this way can be obtained the maximum heeling angle of the *Sylvana* by means of the reduced rolling phenomenon.

Assume that the ship *Sylvana* is affected by sea waves of a frequency of oscillation of γ' and greatest angle of inclination of φ_0' . To reproduce by the pendulum the maximum heeling angle of the *Sylvana* obtained by the n times reduced rolling phenomenon it is necessary to realize the angular velocity of the shaft 58 of $n\gamma'$, a reduction of the values of I_x and I_y by n^2 times and a reduction of the values of I_z and m_z by n times. Since we assume that the shape of the ocean waves and therefore the greatest angle of their inclination, φ_0' , remain unchanged it is concluded that the amplitude $M_s \varphi_0'$, of the rolling moment is unchanged because the moment of oscillation M_s of the pendulum remains constant. Since $M_s \varphi_0'$ is unchanged the value of the expression

$$\frac{I \omega_2 r \gamma' n}{R}$$

must remain unchanged since

$$M_s \varphi_0' = \frac{I \omega_2 r \gamma' n}{R}$$

But the ratio

$$\frac{r}{R}$$

equals the greatest angle of inclination of the waves and is therefore unchanged. Consequently the product $I \omega_2 r \gamma' n$ is unchanged. Since in the foregoing example the frequency of oscillation, γ' , of the ocean waves has been increased

n times the moment of inertia of the gyroscope 71 must be reduced n times so that

$$I' = \frac{I}{n}$$

These changes can readily be realized by the described apparatus. The angular velocity of the shaft 58 can be increased n times so that it equals $n\gamma'$ by means of the series of gears 56 and 57. The movable weights 43 to 50, inclusive, and the movable weights 79 to 82, inclusive, serve to reduce the moment of inertia, I_y , of the pendulum about its axis of swing and the moment of inertia, I_x , of the gyroscope 74, its ring and all members connected with it about its transverse axis 76 by n^2 times. To reduce the moment of inertia I_x by 10 times we can remove the corresponding number of discs from rods 83 and 84. The apparatus is so designed that when the weights 43 to 50, inclusive, are moved as close as possible to the axis of swing of the pendulum, the moment of inertia I_y is reduced by 10 times. Thus, if we want to use $\sqrt{10}$ times reduced rolling phenomenon to reproduce the biggest angle of heel of the *Sylvana* when it is affected by ocean waves having a frequency of oscillation of γ' , we must, in addition to the movement of the noted weights as set forth, increase the angular velocity of the shaft 58 by $\sqrt{10}$. Finally the moments of inertia I_z and I as well as the brake number, m_z , must be reduced by $\sqrt{10}$ times, which is done by putting the necessary weights or flywheels to the shafts of the motors 70 and 75, and by moving the poles of the electromagnet 78 or by changing the current in the electromagnet.

When all this has been accomplished the swing of the pendulum reproduces the maximum heeling angle of the *Sylvana* when it is affected by ocean waves having a frequency of oscillation of γ' and greatest angle of inclination of φ_0' . Otherwise, if it is desired to obtain not only the maximum heeling angle of the *Sylvana* but to investigate by what values of ratios

$$\frac{m_z}{I_x} \text{ and } \frac{I_x^2 \omega^2}{I_x I_y}$$

50 this angle can be reduced as much as possible it becomes necessary by experiment to change the values of m_z and I_z until the correct values of these factors are determined.

When we have become acquainted with the use of the method of reduced rolling phenomenon we can use our apparatus to investigate the rolling motion of any ship whose frequency of oscillation is k times smaller than the minimum frequency of oscillation,

$$\sqrt{\frac{M_s}{I_y \text{ max.}}}$$

60 of the pendulum, which is obtained when the weights 43 to 50, inclusive, are at the greatest distance from the axis of swing of the pendulum. As to the effect upon the size of the pendulum it is not desirable to increase the length of the rods on which weights 43 to 50, inclusive, and 79 to 82, inclusive, are mounted or the size of the weights. We can consider, however, that the rods are lengthened and the weights moved away from the corresponding axis to the extent necessary to increase the moments of inertia $I_y \text{ max.}$ and $I_x \text{ max.}$ K^2 times. In terms of frequency of oscillation

tion this signifies a reduction in the frequency of oscillation of the pendulum,

$$\sqrt{\frac{M_s}{I_y \text{ max.}}}$$

and in the frequency of oscillation of the gyroscope 14,

$$\sqrt{\frac{m_s}{I_z \text{ max.}}}$$

K times so as to make them equal to the values

$$\sqrt{\frac{M_s''}{I_y''}} \text{ and } \sqrt{\frac{m_s''}{I_z''}}$$

of the ship under consideration. Stated algebraically, these equations become

$$\frac{1}{K} \sqrt{\frac{M_s}{I_y \text{ max.}}} = \sqrt{\frac{M_s''}{I_y''}}$$

and

$$\frac{1}{K} \sqrt{\frac{m_s}{I_z \text{ max.}}} = \sqrt{\frac{m_s''}{I_z''}}$$

Also the swing number and the ratio

$$\frac{m_s}{I_z}$$

define the swing of the pendulum as well as the rolling motion of the considered ship. Since $I_y \text{ max.}$ and $I_z \text{ max.}$ are considered as being increased K^2 times, the swing number of the pendulum,

$$\frac{I_z^2 \omega^2}{I_y \text{ max. } I_z \text{ max.}}$$

becomes

$$\frac{I_z^2 \omega^2}{I_y \text{ max. } K^2 I_z \text{ max. } K^2}$$

that is, the swing number is reduced K^4 times. Since the swing number of the pendulum and of the considered ship, represented as N, are equal the equation

$$N = \frac{I_z^2 \omega^2}{K^4 I_y \text{ max. } I_z \text{ max.}}$$

is obtained. This is accomplished by adding the necessary weights axially to the gyroscope 14 so that the moment of inertia I_z becomes $I_{z'}$. Then

$$\frac{I_{z'}^2 \omega^2}{K^4 I_y \text{ max. } I_{z'} \text{ max.}} = N$$

and

$$I_{z'} = \frac{K^2}{\omega} \sqrt{N I_y \text{ max. } I_{z'} \text{ max.}}$$

Also, the ratio

$$\frac{m_s}{I_{z'} \text{ max.}}$$

is reduced K^2 times since the moment of inertia $I_{z'} \text{ max.}$ of the gyroscope about the transverse axis is increased K^2 times. Since the ratio

$$\frac{m_s}{I_z \text{ max.}}$$

is to equal the corresponding ratio of the ship under consideration m_z becomes $m_{z'}$ which is realized by moving the poles of the electromagnet 78. If Q represents the mentioned ratio of the ship under consideration then

$$Q = \frac{m_{z'}}{K^2 I_z \text{ max.}}$$

or $m_{z'} = Q K^2 I_z \text{ max.}$

Thus to cause the pendulum to represent the

greatest angle of heel of the ship under consideration we must make m_z , I_z , I_x and I_y as big as it is shown above. But to obtain the proper magnitudes of I_x and I_y , the movement of the weights 43 to 50, inclusive, and 79 to 82, inclusive, as noted above, would be necessary. As explained, such movement is undesirable and since without this movement the necessary values for

10

$$\frac{M_s}{I_y \text{ max.}} \text{ and } \frac{m_s}{I_x}$$

cannot be obtained the method of reduced rolling phenomenon is employed to reproduce a maximum angle of deflection of the pendulum equal to the maximum heeling angle of the ship under consideration. As mentioned above the frequency of oscillation of the ship is K times smaller than the minimum frequency of oscillation,

$$\sqrt{\frac{M_s}{I_y \text{ max.}}}$$

of the pendulum. Employing the method of reduced rolling phenomenon the frequency of wave oscillation, γ' is considered increased K times and the shape of the waves unchanged so that the greatest angle of inclination, φ_0 of the waves remains the same.

Using the K times reduced rolling phenomenon, the moment of inertia of the pendulum about its axis of swing, which in the example set forth equals $I_y \text{ max.}$, K^2 is reduced K^2 times so that it becomes equal to $I_y \text{ max.}$. This can be realized by placing the weights 43 to 50, inclusive, at the extreme positions shown. Similarly the moment of inertia of the gyroscope 14 about its transverse axis, $I_x \text{ max.}$, K^2 is reduced K^2 times and becomes $I_x \text{ max.}$. This is obtained by positioning the weights 79 to 82, inclusive, as shown. The magnitudes of the brake number and the moment of inertia of the gyroscope 14 about its own axis must also be reduced and by an amount equal to K times. The brake number $Q K^2 I_x \text{ max.}$ then becomes $Q K I_x \text{ max.}$, and the moment of inertia of the gyroscope 14

50

$$\frac{K^2}{\omega} \sqrt{N I_y \text{ max. } I_x \text{ max.}}$$

becomes

55

$$\frac{K}{\omega} \sqrt{N I_y \text{ max. } I_x \text{ max.}}$$

The first change is obtained by movement of the poles of the electromagnet or by changing the current in the electromagnet. The second change is obtained by adding the necessary weights axially to the gyroscope.

60

To summarize the maximum heeling angle of any ship that is stabilized by gyroscope and the frequency of oscillation of which is K times smaller than the frequency of oscillation of the ship upon which is based the construction of laboratory apparatus, can be reproduced in the following manner:

70

1. The weights 43 to 50, inclusive, are placed as far from the axis of swing of the pendulum as possible.
2. The weights 79 to 82, inclusive, are placed as shown.

3. The necessary weights are added to the gyroscope 74 so that its moment of inertia about its own axis equals

$$\frac{K}{\omega} \sqrt{NI_y \text{ max. } I_x \text{ max.}}$$

where N equals the swing number of the ship under consideration.

4. By the use of the movable poles of the electromagnet 78 or by the current in the electromagnet make the brake number equal to QKI_x max., where Q equals

$$\frac{m_s}{I_x}$$

of the considered ship.

5. By means of the series of gears 56 and 57 cause the shaft 58 to rotate with an angular velocity of $K\gamma$ where γ is the frequency of oscillation of the ocean waves.
6. Fasten the bolt 61 to the disc 59 at such a distance r from the center of the disc that the ratio r/R equals the greatest angle of inclination, of the waves.
7. The necessary weights are added to the gyroscope 71 to make its moment of inertia, I, about its own axis equal to

$$\frac{M_s}{\omega_2 K\gamma}$$

It is to be understood that the form of my invention, herewith shown and described, is to be taken as a preferred example of the same, and that various changes in the shape, size and arrangement of parts may be resorted to, without departing from the spirit of my invention; or the scope of the subjoined claims.

I claim:

1. Apparatus for determining in the laboratory the stabilizers required to stabilize the rolling motion of ships effected by waves having different frequencies of oscillation comprising a support, a pendulum, a shaft swingably mounting said pendulum on said support, means for oscillating said pendulum, and means on said pendulum for stabilizing the oscillation of said pendulum, said last-named means embodying a gyroscope.

2. The apparatus of claim 1 in which the gyroscope carries means for varying the moment of inertia of the gyroscope about its transverse axis.

3. Apparatus for determining in the laboratory the stabilizers required to stabilize the rolling motion of ships effected by waves having different frequencies of oscillation comprising a support, a pendulum, a shaft swingably mounting said pendulum on said support, a shaft journalled on said pendulum, means on said pendulum for rotating said latter shaft, means on said pendulum for converting the rotation of said latter shaft into a rectilinear reciprocating motion, a gyroscope having a shaft journalled on said pendulum, means operatively connecting said last-mentioned means with said gyroscope shaft for imparting oscillating motion to said gyroscope about the axis of its said shaft, and a stabilizing gyroscope having a shaft journalled on said pendulum.

4. The apparatus of claim 3 in which the means for rotating said second-mentioned shaft includes means for varying the angular velocity thereof.

5. The apparatus of claim 3 in which the means for converting the rotation of said second-

mentioned shaft into rectilinear reciprocating motion is variable.

6. Apparatus for determining in the laboratory the stabilizers required to stabilize the rolling motion of ships effected by waves having different frequencies of oscillation comprising a support, a pendulum, a shaft swingably mounting said pendulum on said support, means for oscillating said pendulum, and means including a gyroscope for stabilizing the swing of the pendulum, said latter means also including means for exerting a braking moment on said gyroscope in its swinging about its transverse axis.

7. Apparatus for determining in the laboratory the stabilizers required to stabilize the rolling motion of ships effected by waves having different frequencies of oscillation comprising a support, a pendulum, a shaft swingably mounting said pendulum on said support, means for oscillating said pendulum, and means on said pendulum for stabilizing the oscillation of said pendulum, said latter means embodying a gyroscope having a transverse shaft journalled in said pendulum at a right angle to said shaft of said pendulum, a disc secured to one end of said transverse shaft, and an electromagnet having adjustable poles, said disc lying between said poles.

8. Apparatus for determining in the laboratory the stabilizers required to stabilize the rolling motion of ships effected by waves having different frequencies of oscillation comprising a support, a pendulum, a shaft swingably mounting said pendulum on said support, means including a gyroscope for oscillating said pendulum, and means on said pendulum including a gyroscope for stabilizing the oscillation of said pendulum, a gear mounted upon said shaft and oscillating with said pendulum, a guide secured to said support, a rack bar slidably mounted on said guide and meshing with said gear, a stylus secured to said rack bar, and a drum journalled on said support, said stylus cooperating with said drum in the production of indicator diagrams.

9. Apparatus of the character described comprising a support, a pendulum, a shaft swingably mounting said pendulum on said support, a motor mounted on said pendulum, a shaft journalled on said pendulum, variable speed mechanism operatively connecting said motor with said latter shaft, means on said pendulum for converting the rotation of said latter shaft into vertical reciprocating motion, a gyroscope having a transverse shaft journalled on said pendulum, means including a member mounted on said transverse shaft connecting said first-mentioned means with said transverse shaft for effecting oscillation of said gyroscope about said transverse shaft, and a stabilizing gyroscope having a transverse shaft journalled on said pendulum.

10. Apparatus of the character described comprising a support, a pendulum, a shaft swingably mounting said pendulum on said support, a motor mounted on said pendulum, a shaft journalled on said pendulum, variable speed mechanism operatively connecting said motor with said latter shaft, variable means on said pendulum for converting the rotation of said latter shaft into vertical reciprocating motion, a gyroscope having a transverse shaft journalled on said pendulum, means including a member mounted on said transverse shaft connecting said first-mentioned means with said transverse shaft for effecting oscillation of said gyroscope about said transverse shaft, and a stabilizing gyroscope having a transverse shaft journalled on said pendulum.

11. Apparatus of the character described comprising a support, a pendulum, a shaft swingably mounting said pendulum on said support, a motor mounted on said pendulum, a shaft journalled on said pendulum, variable speed mechanism operatively connecting said motor with said latter shaft, a slide mounted on said pendulum, means connecting said latter shaft with said slide and converting the rotation of said latter shaft into reciprocating rectilinear motion of said slide, a gyroscope having a transverse shaft journalled on said pendulum, means connected with said slide and a member mounted on said transverse shaft for converting the reciprocating motion of said slide into oscillating motion of said gyroscope, and a stabilizing gyroscope having a transverse shaft journalled on said pendulum.

12. Apparatus of the character described comprising a support, a pendulum, a shaft swingably mounting said pendulum on said support, means associated with said pendulum for varying its moment of inertia about the axis of said shaft, a motor mounted on said pendulum, a shaft journalled on said pendulum, variable speed mechanism operatively connecting said motor with said latter shaft, variable means on said pendulum for converting the rotation of said latter shaft into vertical reciprocating motion, a gyroscope having a transverse shaft journalled on said pendulum, means including a member mounted on said transverse shaft connecting said variable means with said transverse shaft for effecting oscillation of said gyroscope, and a stabilizing gyroscope having a transverse shaft journalled on said pendulum.

13. Apparatus of the character described comprising a support, a pendulum, a shaft swingably mounting said pendulum on said support, means associated with said pendulum for varying its moment of inertia about the axis of said shaft, a motor mounted on said pendulum, a shaft journalled on said pendulum, variable speed mechanism operatively connecting said motor with said latter shaft, variable means on said pendulum for converting the rotation of said latter shaft into vertical reciprocating motion, a gyroscope having a transverse shaft journalled on said pendulum, means including a member mounted on said transverse shaft connecting said first mentioned means with said transverse shaft for effecting oscillation of said gyroscope, a stabilizing gyroscope having a transverse shaft journalled on said pendulum, means associated with said stabilizing gyroscope to vary its moment of inertia about the axis of its transverse shaft, and means associated with said stabilizing gyroscope to vary its moment of inertia about its own axis.

14. Apparatus of the character described com-

prising a support, a pendulum, a shaft swingably mounting said pendulum on said support, means associated with said pendulum for varying its moment of inertia about the axis of said shaft, a motor mounted on said pendulum, a shaft journalled on said pendulum, variable speed mechanism operatively connecting said motor with said latter shaft, variable means on said pendulum for converting the rotation of said latter shaft into vertical reciprocating motion, a gyroscope having a transverse shaft journalled on said pendulum, means associated with said gyroscope for varying its moment of inertia about its own axis, means including a member mounted on said transverse shaft connecting said first mentioned means with said transverse shaft for effecting oscillation of said gyroscope, a stabilizing gyroscope having a transverse shaft journalled on said pendulum, means associated with said stabilizing gyroscope to vary its moment of inertia about the axis of its transverse shaft, and means associated with said stabilizing gyroscope to vary its moment of inertia about its own axis.

15. Apparatus of the character described comprising a support, a pendulum, a shaft swingably mounting said pendulum on said support, means associated with said pendulum for varying its moment of inertia about the axis of said shaft, a motor mounted on said pendulum, a shaft journalled on said pendulum, variable speed mechanism operatively connecting said motor with said latter shaft, variable means on said pendulum for converting the rotation of said latter shaft into vertical reciprocating motion, a gyroscope having a transverse shaft journalled on said pendulum, means associated with said gyroscope for varying its moment of inertia about its own axis, means including a member mounted on said transverse shaft connecting said first mentioned means with said transverse shaft for effecting oscillation of said gyroscope, a stabilizing gyroscope having a transverse shaft journalled on said pendulum, means associated with said stabilizing gyroscope to vary its moment of inertia about the axis of its transverse shaft, and means associated with said stabilizing gyroscope to vary its moment of inertia about its own axis.

16. Apparatus of the character described comprising a support, a pendulum, a shaft swingably mounting said pendulum on said support, means associated with said pendulum for varying its moment of inertia about the axis of said shaft, a motor mounted on said pendulum, a shaft journalled on said pendulum, variable speed mechanism operatively connecting said motor with said latter shaft, variable means on said pendulum for converting the rotation of said latter shaft into vertical reciprocating motion, a gyroscope having a transverse shaft journalled on said pendulum, means associated with said gyroscope for varying its moment of inertia about its own axis, means including a member mounted on said transverse shaft connecting said first mentioned means with said transverse shaft for effecting oscillation of said gyroscope, a stabilizing gyroscope having a transverse shaft journalled on said pendulum, means associated with said stabilizing gyroscope to vary its moment of inertia about the axis of its transverse shaft, and means associated with said stabilizing gyroscope to vary its moment of inertia about its own axis.
